US0D1025895S

(12) **United States Design Patent** (10) **Patent No.:** **US D1,025,895 S**
(45) **Date of Patent:** **** May 7, 2024**

(54) **BATTERY CHARGER**

(71) Applicant: **Shenzhen Ningxin Juli Technical Service Co., Ltd.**, Shenzhen (CN)

(72) Inventor: **Yongping Huang**, Shenzhen (CN)

(**) Term: **15 Years**

(21) Appl. No.: **29/927,167**

(22) Filed: **Feb. 2, 2024**

(51) LOC (14) Cl. **13-02**

(52) U.S. Cl.

USPC **D13/107**

(58) **Field of Classification Search**

(57) **CLAIM**

The ornamental design for a battery charger, as shown and described.

DESCRIPTION

FIG. 1 is a perspective view of a battery charger;
FIG. 2 is a top plan view thereof;
FIG. 3 is a bottom plan view thereof;
FIG. 4 is a left side elevational view thereof;
FIG. 5 is a right side elevational view thereof;
FIG. 6 is a front elevational view thereof;
FIG. 7 is a rear elevational view thereof;
FIG. 8 is an enlarged view of portion 8 shown in FIG. 1; and,
FIG. 9 is an enlarged view of portion 9 shown in FIG. 1.
The broken lines in the drawings depict portions of the
battery charger that form no part of the claimed design.
The dot-dash broken lines represent boundaries of the
enlarged portions and form no part of the claimed design.

1 Claim, 9 Drawing Sheets
